UNITED STATES PATENT OFFICE.

EDWARD SPENCER HALL, OF NEW YORK, N. Y.

BRAKE FOR BICYCLES.

SPECIFICATION forming part of Letters Patent No. 554,419, dated February 11, 1896.

Application filed June 25, 1895. Serial No. 553,973. (No model.)

To all whom it may concern.

Be it known that I, EDWARD SPENCER HALL, of the city, county, and State of New York, have invented a new and useful Improvement 5 in Brakes for Bicycles, of which the following is a full description.

The accompanying drawings illustrate the invention, of which—

Figure 1 is a plan view of the brake applied 10 to an axle; Fig. 2, an end section taken on line x x , Fig. 1; and Fig. 3 a detail view of part of band-brake and sustaining-bar.

This invention is an improvement upon the band-brake for which I have an application 15 in the Patent Office, bearing the Serial No. 524,966, and which was allowed on the 21st day of February, 1895. I have discovered that the method as illustrated by the drawings in that application of securing the end of 20 the band-brake therein shown would tend to direct the pull of the brake upon one side of the ball-bearings of the journals and hence induce more wear on that side. I therefore have invented an independent device to 25 which that end of the band-brake is attached, and while it diminishes this pressure upon one side of the ball-bearings it also furnishes a wider bearing-surface upon the axle and aids in applying the brake.

30 In the drawings, H is the crank-shaft upon which the band-brake is wound.

I is the band-brake coiled upon the axle, which consists of a coil or cord, wire, or band made of suitable material, and if of metal may 35 be properly tempered to give it sufficient spring to return it to normal when released. The brake should be so wound upon the shaft that when drawn in contact therewith the tendency of the shaft to turn will assist in 40 tightening the brake. To one end of this band-brake is secured the cord or rod i, which proceeds through the tubing to the handle of the bicycle, which is provided with means for drawing it. The other end of the band-brake 45 is attached to an independent bar or rod A. For convenience I have provided this end of

the band with the shoulders i' i'' and one end of the bar A with a slot a^2 to pass behind the shoulder and hold that end of the band. It may be attached by any other method, if desired. The other end of the independent bar passes through an opening or slot in the tube and need not be otherwise secured or fastened. For convenience I have also scooped out the bar, as shown at a^3 , to conform in 55 shape to the axle and give a good bearing-surface thereon, and this bearing-surface gives material aid to the action of the brake on the shaft, while at the same time the construction above described diminishes the tendency of 60 the shaft to be drawn toward and work upon one side of the ball axle-bearings.

What I claim, and desire to secure by Letters Patent, is—

1. In a brake for a bicycle and axle inclosed 65 within a tube, in combination with a band-brake coiled upon the axle within the tube, having one of its ends connected with the actuating devices of the brake, and an independent bar having one of its ends attached to the 70 opposite end of the band, and its other end passed through a slot in the tube inclosing the axle, and adapted to contact with the axle at a point between the end attached to the brake and the slot in the tube. 75

2. In a brake for a bicycle an axle inclosed within a tube, in combination with a band-brake coiled upon the axle within the tube, having one of its ends connected with the actuating devices of the brake and its other end 80 attached to the extremity of an independent bar, the latter scooped out to conform to the shape of the axle, and means for holding the free end of the independent bar substantially as described. 85

Signed at New York, in the county of New York and State of New York, this 22d day of June, A. D. 1895.

E. SPENCER HALL.
